UNITED STATES PATENT OFFICE.

NEIL MACNEALE, OF CINCINNATI, OHIO, ASSIGNOR, BY MESNE ASSIGNMENTS, TO THOMSON ELECTRIC WELDING COMPANY, OF LYNN, MASSACHUSETTS, A CORPORATION OF MASSACHUSETTS.

ELECTRIC RIVETING APPARATUS.

1,297,965.

Specification of Letters Patent. Patented Mar. 18, 1919.

Application filed August 25, 1916. Serial No. 116,738.

To all whom it may concern:

Be it known that I, NEIL MACNEALE, a citizen of the United States, residing at Cincinnati, in the county of Hamilton and State of Ohio, have invented certain new and useful Improvements in Electric Riveting Apparatus, of which the following is a full, clear, and exact specification.

The principal object of my invention is to provide a new and improved machine for heading rivets involving a preliminary heating of them electrically. Another object of my invention is to provide a riveting machine with an electrode and a riveting die that may be applied successively, the electrode to complete an electric circuit through the rivet to heat it, and the die to be applied thereafter to head the rivet. Still another object of my invention is to provide an electric riveting machine with an anvil to receive the head of the rivet and a reciprocable member in opposition to the anvil carrying both an electrode and a riveting die, either of which may be applied alternatively to the rivet. All these objects and others will be apparent in the following specification and claims taken with the accompanying drawings in which I have illustrated one specific embodiment of my invention. It will be understood that the invention is defined in the appended claims. I now proceed to describe the particular embodiment of my invention which is shown in the drawings.

Figure 1 is a side elevation of the embodiment of my invention which I have chosen to describe in this specification;

Fig. 2 is a partial front elevation of the same in conjunction with a diagrammatic representation of the electric circuits therefor, and

Fig. 3 is an elevation partly in section of a certain valve and associated elements which are hidden from view in Fig. 1.

The frame 11 carries an adjustable copper bracket 12 on the copper guide 24 which is insulated from the frame at 25. On the copper bracket 12 is a lower copper die or anvil holder 13 carrying the copper die or a rivet 14 (which also serves as an electrode) adapted to receive the head of a rivet 15.

The upper part of the frame 11 has suitable vertical guides in which the member 16 is adapted to slide up and down. This member 16 has a copper electrode holder 17

bolted to its lower end by the bolts 19 and 55 separated therefrom by insulation 18. The copper electrode holder 17 carries a copper electrode 20 in alinement with the anvil 14.

Flexible copper strips 21 are bolted to the copper holder 17 and connected to one terminal of the secondary of the transformer 22, the other terminal 23 being connected to the guide plate 24 that carries the bracket 12.

The lower end of the reciprocable member 16 has a pair of horizontal guides 26, in 65 which are the slides 27 carrying the depending member 28 with a die 29 at its lower end adapted in one position to engage the rivet 15. A bell crank is pivoted on the reciprocable member 16 with a handle 32 connected 70 to one arm 31, and the other arm 30 engages the die member 28 so that by operating the handle 32 this die member 28 can be displaced horizontally on the lower end of the sliding member 16. 75

A toggle joint 33 is connected to the upper end of the vertical reciprocable member 16, and the tension spring 34 normally holds the toggle broken, and raises the member 16, in which the spring 35 acting on the lever 36 80 assists. The air cylinder 37 has a piston 38 connected by a rod 41 to the toggle 33. The cylinder 37 is pivoted at 39 and carries a counterweight 40.

A pressure air pipe 42 leads directly 85 through a branch 46 to the valve casing 43, and through a pressure reducer 48 and another branch 47 to another port of the same casing 43. This casing 43 also has a port 44 connected by a pipe to the cylinder 37 behind the piston 38, and the casing 43 also has an exhaust port 49. Within the casing 43 is the valve member 45 carrying the crank 50 and handle 51. As will be seen from Fig. 3, a downward movement of the handle 51 connects the cylinder 37 to receive high pressure air, an upward movement of the handle 51 connects to receive lower pressure air, and an intermediate position of the handle 51 connects the cylinder 37 to the exhaust. 95

In the handle 51 is a thumb operated switch 52 adapted to connect the conductors 53 which are in a local circuit with the magnet 54. The latter, when energized, attracts 105 its armature 55 and closes at 56 the primary circuit of the transformer 22 from the alternating current generator 57.

The work to be riveted is brought in such position that the head of a rivet rests on the electrode anvil 14. The handle 32 is pulled down thus displacing the die 29 to the right 5 of the position shown in Fig. 1. The handle 51 is raised admitting low pressure air through the valve 45 behind the piston 38 which acts on the toggle 33 to push the electrode 20 down against the rivet 15. At the 10 same time a switch 52 is operated by the thumb of the hand on the handle 51 closing the circuit through the magnet 54 and thus closing at 56 the primary circuit of the transformer 22. The secondary circuit of 15 this transformer having been closed through the electrode 14, rivet 15 and electrode 20, a current of high amperage and low voltage goes therethrough heating the rivet to a suitable degree for heading. Thereupon, 20 the thumb switch 52 is opened, thus cutting off the supply of current through the rivet and the handle 51 is lowered to its intermediate position connecting the cylinder 37 to the exhaust port 49, permitting the spring 25 34 to break the toggle 33 and with the assistance of spring 35 raise the member 16 and thereby raise the electrode 20 from the rivet 15. Next the handle 32 is pushed up to the position shown in the drawings, thus 30 bringing the riveting die 29 to a position in alignment with the rivet 15. Then the handle 51 is pulled down from its intermediate position so as to connect the valve 45 to transmit high pressure air to the cylinder 35 37. This straightens the toggle 33 and lowers the member 16 forcing the die 29 on the rivet 15 and suitably heading the same. Returning the handle 51 to its intermediate position permits the cylinder 37 to exhaust 40 through the port 49 so that the springs 34 and 35 again raise the member 16. This completes a cycle of operations for heating and heading the rivet 15.

It will be seen that I have provided a 45 comparatively simple and convenient device by which two different members may be applied in succession to a rivet resting on the anvil, the first member acting as an electrode to supply an electric current to the 50 rivet for heating it, and the second member acting as a riveting die. With my improved machine the operating of heating and heading the rivets 15 can be performed very rapidly and effectively.

Having thus described my invention, I declare that what I claim as new and desire to 55 secure by Letters Patent, is:—

1. In an electric riveter, an electrode anvil to receive the head of a rivet, an opposed 60 member movable to or from the anvil, an electrode carried by said member, a riveting die also carried by said member, one of said two elements that are carried by said member being displaceable laterally relatively to 65 the member so as to throw it in or out of

alignment with said anvil, whereby either said element may be brought into engagement with the rivet, and means to supply an electric current through said electrodes and an interposed rivet. 70

2. In an electric riveter, an electrode anvil to receive the head of a rivet, an opposed member movable to or from the anvil, an electrode carried by said member, a riveting die also carried by said member, one 75 of said two elements that are carried by said member being located permanently in alignment with the said anvil, the other such element carried by said member being displaceable laterally relatively to the member so as to throw it in or out of alignment with said anvil, whereby either said element may be brought into engagement with the rivet, and means to supply an electric current through said electrodes and an interposed rivet. 80

3. In an electric riveter, an electrode anvil to receive the head of a rivet, an opposed member movable to or from the anvil, an electrode fixed thereon in alignment with 90 said anvil, a riveting die mounted on said member and adapted to be displaced laterally relatively to said member, and in one position to be brought between said anvil and said electrode, and means to supply an 95 electric current through said electrodes and an interposed rivet.

4. In an electric riveter, an electrode anvil to receive the head of a rivet, an opposed member movable to or from the anvil, an 100 electrode fixed on said member, a transverse guide on said member, a riveting die carried in said transverse guide and adapted in one position to be between said electrode and said anvil, and means to supply an electric 105 current through said electrodes and an interposed rivet.

5. In an electric riveter, an electrode anvil to receive the head of a rivet, an opposed member movable to or from the anvil, an 110 electrode carried by said member, a riveting die also carried by said member and displaceable laterally relatively thereto, a lever pivoted on the member, and engaging said riveting die at one point and having a handle at another point, and means 115 to supply an electric current through said electrodes and an interposed rivet.

6. In an electric riveter, an electrode anvil to receive the head of a rivet, an opposed member movable to or from the anvil, an electrode and a riveting die carried by 120 said member and adapted to be applied alternatively to a rivet on the anvil, a fluid pressure motor for said member, a high 125 pressure fluid source, a low pressure fluid source, and means to connect either source to said motor.

7. In an electric riveter, an electrode anvil to receive the head of a rivet, an opposed 130

- member movable to or from the anvil, an electrode and a riveting die adapted to be applied by said member alternatively to a rivet on the anvil, a fluid pressure motor 5 to move said member to or from the anvil, a pressure fluid source, a valve to control the same, a handle for said valve, an electric current source and conductors to carry current through said electrodes and an interposed rivet, and a control switch for such current with its operated member in the handle of said valve.
8. In an electric riveter, an electrode anvil to receive the head of a rivet, an opposed 15 member movable to or from the anvil, an electrode and a riveting die adapted to be applied by said member alternatively to a rivet on the anvil, a fluid pressure motor for said member, a high pressure fluid 20 source, a low pressure fluid source, a valve adapted to connect said motor to either source or to exhaust the motor, a handle for said valve, an electric circuit adapted to be completed through said electrodes and 25 an interposed rivet, and a control switch for said circuit with its operated member in the handle of said valve.
9. In an electric riveter, an electrode anvil to receive the head of a rivet, an opposed 30 member movable relatively to or from the anvil, an electrode and a riveting die both carried by said opposed member, one of said two elements that are carried by said opposed member being relatively displaceable laterally so as to throw it in or out of aline- 35
- ment with said anvil, whereby either said element carried by said opposed member may be brought into engagement with the rivet, and means to supply an electric current through said electrodes and an interposed rivet. 40
10. In an electric riveter, an electrode anvil to receive the head of a rivet, an opposed member movable to or from the anvil, an electrode and a riveting die carried by 45 said member and adapted to be applied thereby alternatively to the rivet or said anvil, fluid pressure means to operate said member, a control valve therefor, a handle for said valve, means to send a heating current through said electrode and a rivet between the same and said anvil, and a control switch for said means in said valve handle. 50
11. In an electric riveter, an electrode anvil to receive the head of the rivet, an electrode and a riveting die adapted to be applied alternatively to a rivet on said anvil, fluid pressure means for said riveting die, a valve to control the same, a handle for said valve, means to send an electric current through said electrode and said anvil and an interposed rivet to heat the latter, and a control switch for said current in the handle of said valve. 55

In testimony whereof I affix my signature, in presence of two witnesses. 65
